UNITED STATES PATENT OFFICE.

WILLIAM C. STEFFAN, FRANK B. ACKERMANN, AND WALTER J. GREINER, OF CHICAGO, ILLINOIS.

DESIGN FOR A PENCIL.

Application filed August 13, 1921. Serial No. 492,167. Term of patent 14 years.

To all whom it may concern:

Be it known that we, WILLIAM C. STEFFAN, FRANK B. ACKERMANN, and WALTER J. GREINER, citizens of the United States, residing at Chicago, in the county of Cook and State of Illinois, have invented a new, original, and ornamental Design for Pencils, of which the following is a specification, reference being had to the accompanying drawing, forming a part thereof.

The figure is a side elevation of a pencil showing our new design.

We claim:

The ornamental design for a pencil as shown.

WM. C. STEFFAN.
F. B. ACKERMANN.
W. J. GREINER.
